(57) **CLAIM**

The ornamental design for a pollen trap for a beehive, as shown and described.

DESCRIPTION

The patent or application file contains at least one drawing executed in color. Copies of this patent or patent application publication with color drawing(s) will be provided by the Office upon request and payment of the necessary fee.

1.1 is a front view of a pollen trap for a beehive;

1.2 is a detailed view thereof.

The blue tint in reproductions 1.1 and 1.2 show environmental structure or boundaries that form no part of the claimed design and is hereby disclaimed. The environmental structure that is visible through the holes of the pollen trap in reproduction 1.1 form no part of the claimed design and is hereby disclaimed.

1 Claim, 2 Drawing Sheets
(2 of 2 Drawing Sheet(s) Filed in Color)
